UNITED STATES PATENT OFFICE.

WILLIAM CAMPBELL, OF DETROIT, MICHIGAN.

DEFLECTOR FOR THE SHAFT-BEARINGS OF DISH-WASHING MACHINES.

1,235,288.

Specification of Letters Patent. Patented July 31, 1917.

Application filed November 15, 1916. Serial No. 131,371.

To all whom it may concern:

Be it known that I, WILLIAM CAMPBELL, a citizen of the United States of America, residing at Detroit, in the county of Wayne 5 and State of Michigan, have invented certain new and useful Improvements in Deflectors for the Shaft-Bearings of Dish-Washing Machines, of which the following is a specification, reference being had there- 10 in to the accompanying drawings.

This is an improvement in connection with a dish washing machine disclosed by my Patent No. 1,178,213, granted April 4, 1916.

In this patent there is shown and described 15 a combined kitchen table and dish washing machine, the table including a hinged lid by which easy access is had to the interior of the dish washing machine. The lid is provided with a stop member to limit the opening movement of the same by contacting with the rear wall of the machine, and this stop member was found to be unsatisfactory as it did not prevent accidental closing of the lid.

20 One of my improvements is to provide an end wall of the dish washing machine with a simple and effective lid holding device, which can be manually manipulated to positively hold the lid of the machine in an open 25 position.

My prior patent also discloses a driven agitator shaft journaled in the front and rear walls of the dish washing machine and associated with the shaft bearing at the rear 30 wall of the machine is a non-leakable wall joint and deflector. After placing the washing machines on the market, there were complaints of leakage around the agitator shaft at the rear wall of the machine, to overcome 35 which I have devised a reliable and non-leakable bearing for the agitator shaft, which constitutes another improvement over my prior patent.

The detailed construction of each improvement will be hereinafter specifically 40 described and then claimed, and reference will now be had to the drawing, as showing an end view of the dish washing machine, partially broken away and partially in section, to illustrate the agitator shaft bearing, and also showing the lid of the dish washing machine held in an open position.

As in my prior patent and referring to the accompanying drawings, 8 denotes front and 45 rear walls of the dish washing machine in

which is journaled an agitator shaft 24 provided with a driven wheel 27.

9 denotes an end wall and 16 a hinged lid for the dishwashing machine.

Considering the improvement in the manner of journaling the agitator shaft 24 in the rear wall 8 of the machine, 50 denotes a bearing set in an opening 51 provided therefor in the rear wall 8. The rear end of the agitator shaft 24 is journaled in said bearing. The outer end of the bearing 50 has a peripheral flange 52 for snug engagement with the outer side of the wall 8 and the inner end of the bearing 50 is exteriorly 55 screwthreaded as at 53.

Mounted on the inner end of the bearing 50 is a cup shaped deflector 54 and holding said deflector snug against the inner side of the wall is a collar 55 screwed on the inner end of the bearing 50. The collar 55 is 60 housed within the cup shaped deflector 54 and abutting the collar 55 is a disk shaped deflector 56 serving functionally as a closure for the cup shaped deflector 54. The disk shaped deflector 56 is also housed within the 65 deflector 54 and is suitably connected to the agitator shaft 24, as at 57.

As a result of this construction, the peripheral flange 52 of the bearing 50 and the cup shaped deflector 54 are firmly clamped 70 against the wall 8 by the collar 55, and with the cup shaped deflector 54 made of tin or a light and thin material, a positive connection is established with the rear wall 8. The cup shaped deflector 54 will tend to deflect 75 water from around the journal of the agitator shaft 24 and the disk shaped deflector 56 tends to exclude water from the deflector 54. This construction has been found satisfactory and positively provides a reliable 80 and non-leakable journal for the agitator shaft at the rear wall of the dish washing machine.

Considering the improvement in connection with the lid 16 of the dish washing machine, it is to be noted that the lid is of 85 greater area than the open top of the machine and consequently projects from the walls 8 and 9 when closed. Pivotally connected to the end wall 9, as at 60, is a hand 90 lever 61 extending forwardly within convenient reach from in front of the dish washing machine. The rear end of the lever 61 is twisted a quarter of a revolution to provide a horizontal portion 62 having an up- 95

turned end 63 and riveted or otherwise secured to the horizontal portion 62, as at 64, is an angle arm 65 coöperating with the up-turned end 63 in providing a yoke or U-shaped holder. The hand lever 61 is balanced so that when the yoke is not in engagement with the rear edge of the lid 16, the arm 65 will engage the rear wall 8 of the dish washing machine as shown by dotted lines in the drawings. As the lid 16 is opened with one hand, the hand lever 61 is elevated to lower the yoke and provide clearance for the rear edge of the lid 16, at which time the lever 61 is lowered to bring the yoke 15 into engagement with the rear edge of the lid, and thus positively hold the lid against accidental closing. To release the lid, it is only necessary to elevate the forward end of the hand lever 61, thus removing the yoke 20 from the rear edge of the lid 16, at which time the lid may be lowered.

What I claim is:—

1. In a dish washing machine having rear and end walls, an agitator shaft extending

through the rear wall, a bearing in said rear wall for said agitator shaft, a cup shaped deflector on said bearing against said rear wall, a collar mounted on said bearing and holding said cup shaped deflector against said rear wall, and a disk shaped deflector on said agitator shaft in said cup shaped deflector.

2. In a dish washing machine having rear and end walls, an agitator shaft extending through the rear wall, a bearing in said rear wall for said agitator shaft, a cup shaped deflector on said bearing against said rear wall, a deflector on said agitator shaft in said cup shaped deflector, and means on said bearing within said cup shaped deflector for holding said cup shaped deflector against said rear wall.

In testimony whereof I affix my signature in the presence of two witnesses.

WILLIAM CAMPBELL.
